MOTION PICTURE CAMERA

Robert E. Bourke, Goodhill Road,
Weston, Conn. 06880

Filed May 22, 1969, Ser. No. 17,276

Term of patent 14 years

Int. Cl. D16—02

U.S. Cl. D61—1

FIG. 1

FIG. 2

FIG. 3

FIG. 4

FIG. 5

FIG. 7

FIG. 6

FIG. 1 is an isometric view of a motion picture camera or the like embodying my new design;

FIG. 2 is a front elevational view thereof;

FIG. 3 is a top plan view thereof;

FIG. 4 is a bottom plan view thereof;

FIG. 5 is a side elevational view thereof;

FIG. 6 is an elevational view of the side of the camera opposite to that depicted in FIG. 5; and

FIG. 7 is a rear elevational view thereof.

I claim:

The ornamental design for a motion picture camera, substantially as shown.
